UNITED STATES PATENT OFFICE.

DALLAS F. GRAHAME, OF TORONTO, ONTARIO, CANADA, ASSIGNOR TO HYDROSTATIC JACKS, LIMITED, OF TORONTO, CANADA.

HYDROSTATIC JACK.

Application filed September 2, 1922. Serial No. 586,377.

To all whom it may concern:

Be it known that I, DALLAS F. GRAHAME, of the city of Toronto, in the county of York, Province of Ontario, Canada, a subject of the King of Great Britain, have invented certain new and useful Improvements in Hydrostatic Jacks, of which the following is a specification.

This invention relates to jacks of the type in which the shoe of the jack is connected to a plunger operating in a cylinder and in which the plunger is extended by pumping the working liquid from the upper to the lower side of the plunger and my object is to devise simple means for permitting the liquid to flow back and thus lower the plunger. A further object is to provide means for preventing the jack operating liquid from overflowing between the cylinder and the plunger.

I attain my object by means of the constructions hereinafter described and illustrated in the accompanying drawings in which:

Fig. 1 is a side elevation of a jack constructed in accordance with my invention;

Fig. 2 a plan view of the same;

Fig. 3 a vertical section of the jack cylinder showing the conduit in position to elevate the plunger and shoe;

Fig. 4 a vertical section of the upper part of the plunger showing the conduit in position to lower the plunger and the shoe;

Fig. 5 a horizontal section on the line V to V in Fig. 3;

Fig. 6 a detail in section of the air admitting checkvalve; and

Fig. 7 a detail in section of a modified form of an air admitting and exhausting valve.

In the drawings like numerals of reference indicate corresponding parts in the different figures.

1 is the cylinder of the jack suitably carried by the base 2. This cylinder is closed at its lower end and is provided with a stuffing box 3 at its upper end. Slidably mounted in the cylinder is the tubular plunger 4 in the upper end of which is suitably secured the lifting shoe 5 forming an air tight joint at the upper end of the plunger. A disk 6 is fitted within the lower end of the plunger to close this end and to the underside of the disk is secured a cup shaped washer 7 as hereinafter described.

In the interior of the lifting shoe 5 are formed the passages 8, 9 and 10 for valves 8^a and 9^a controlling the movement of the operating liquid of the jack. To raise the jack the liquid is pumped from the tubular plunger 4 to the cylinder 1 below the plunger and to lower the jack the liquid is permitted to flow back as hereinafter described. The vertical passages 8 and 9 communicate at their upper ends with the horizontal passage 10, the passages 8 and 10 being provided with the ball check valves 8^a and 9^a respectively, the check valve 9^a being adapted to permit only an upward flow of liquid through the passage 9 and the check valve 8^a being adapted to permit only a downward flow of liquid through the passage 8.

In the lower ends of the passages 8 and 9 are threaded a pair of tubes 8^b and 9^b which extend downwardly and pass through suitable holes formed in the disk 6 and washer 7 and also through holes formed in the washer retaining disk 7^a. On the lower end of the tube 8^b is threaded an open ended nut 8^c and on the lower end of the tube 9^b is threaded a nut 9^c having its lower end closed. The tube 9^b is provided with a lateral opening 9^d which is located slightly above the disk 6. It will readily be seen that the tube 8^b forms a communication between the passages 10 and 8 and the interior of the cylinder 1 below the plunger 4, and that the tube 9^b forms a communication between the passages 10 and 9 and the opening 9^d with the interior of the plunger 4.

11 is a pump barrel and 12 the piston rod of the pump provided with the operating handle 13 (see Figs. 1 and 2). This pump barrel is connected by a pipe joint 14 with the conduit 15. This pipe joint is of the type commonly employed in gas brackets and permits the pump barrel to be hinged on the conduit. The conduit itself is connected by a similar pipe joint 16 with the lifting shoe 5 and this joint forms a communication between the conduit 15 and the passage 10 formed in the lifting shoe. A fluid connection between the pump and the passage 10 is thus provided, while permitting the conduit and pump barrel to be folded on one another and brought into substantially parallel relationship with the jack for convenience of storage. From the above description it is evident that a suction stroke of the pump piston rod 12 will draw the ball 11c

- of the check valve 9^a off its seat to permit a quantity of liquid to be drawn from the interior of the plunger 4 through the opening 9^a, tube 8^a and passage 9 into the passage 5 10 and a stroke of the piston rod 12 in the opposite direction will force this liquid in the passage 10 through the check valve 8^a, passage 8, tube 8^a and finally under the plunger 4 to raise the latter.
- 10 The above method of raising the lifting shoe of the jack is well known in the art and what I have devised it means, for lowering the lifting shoe, this may be operated by simply lifting the pump barrel 11 on the 15 pipe joint 16 as hereinafter described. The lifting shoe is provided with a liquid filter opening communicating with the interior of the plunger 4 and into this opening is threaded a plug 17 having an aperture 18 communicating with the atmosphere and the interior of the plunger 4. This aperture is automatically closed under normal conditions by the spring and ball check valve 19 suitably mounted within the plug. With this 20 arrangement it is obvious that on each successive stroke of the piston rod 12 of the pump, air will be drawn in through the aperture 18 to replace the amount of oil drawn from the plunger 4 and thus prevent a vacuum 25 above the oil in the tubular plunger. In the lifting shoe 5 is formed a return passage 20 communicating at one end with the passage 8 and at the other end with the return passage 20^a. A separate return passage 21 30 forms a communication between the passage 8 and the return passage 21^a. From this description it follows that if the return passages 20^a and 21^a are brought into communication, and the air above the liquid in the 35 plunger is allowed to escape, the pressure on the lifting shoe and plunger due to the weight of the vehicle that has been lifted will cause the liquid to flow from below the plunger through the return passages and into the upper end of the plunger and thus 40 lower the lifting shoe. The return passages 20^a and 21^a at their upper ends communicate with the opening in the bearing in which is journalized the plug of the joint 16. In this 45 plug is formed a longitudinal groove 22 adapted to be brought into register with the return passages 20^a and 21^a when the plug is oscillated in its bearing which movement is caused by rocking the conduit 15 to the position shown in Fig. 4.
- To permit the air, which has been drawn in through the aperture 18 as hereinbefore described, to escape and thus permit the liquid to flow back above the plunger 4 I 50 form an air outlet opening 23 in the lifting shoe 5 which opening communicates with the interior of the plunger and the atmosphere and is adapted to be normally closed by the plug of the joint 16. This plug is provided 55 with a transverse opening 23^a and adapted

to be brought into register with the opening 23 when the groove 22 is brought into register with the passages 20^a and 21^a. Preferably the groove 22 and opening 23^a are formed in the plug so that by rocking 70 the latter downwardly they are brought into register with their respective openings to permit the jack to be lowered and this arrangement permits the weight of the conduit 15 and the pump barrel 11 to be used for 75 rocking the plug.

In Fig. 7 I show a modified form of air admitting and exhausting means in which a transverse groove 23^b formed in the plug of the joint 16 is adapted to maintain a communication with the opening 23 when the plug is rocked from its lifting position to its lowering position whereby air is admitted or exhausted from the interior of the plunger 4 as the liquid is drawn from or 80 allowed to flow into the plunger respectively. The groove 23^b is also adapted to close the opening 23 to prevent the leakage of liquid therethrough, when the conduit 15 is swung into a substantially parallel position relative 85 to the jack for storage.

In this type of jack there is a great tendency for the liquid under the plunger 4 to be forced upwardly, past the cup shaped washer 7, between the walls of the plunger 4 and cylinder 1 and out through the stuffing box 3 at the upper end of the cylinder. To prevent this overflow I form openings 24 in the cylindrical wall of the plunger 4 and adjacent its lower end. These openings 90 permit the packing of the stuffing box 3 to force any excessive liquid, that has been forced up between the plunger and cylinder walls, back into the plunger.

The mode of operation is as follows. Assuming the plunger 4 has been filled with liquid, the lifting shoe 5 is raised in the usual manner by operating the pump handle 18, which pumps the liquid from above the plunger to below the latter and air is 105 drawn in the plunger to replace the liquid pumped out to prevent back pressure as hereinbefore described. When the movement of the lifting shoe is to be reversed, the free end of the pump barrel 11 is lowered to oscillate the plug of the joint 16 to bring the groove 22 into register with the return passages 20^a and 21^a and the transverse opening 23^a or groove 23^b into register 110 with the exhaust air opening 23. This 115 permits the air to escape and the liquid below the plunger to flow back through the nut 8^a, tube 8^a, passage 8, 20 and 20^a and then through the groove 22 into the passages 21^a, 21 and 9, through the tube 9^a and opening 9^a into the plunger 4. With this 120 arrangement the lowering of the jack is easily effected by simply lowering the free end of the pump barrel and the user of the jack has no need to reach in under the vehicle 125 to the pump handle.

hicle being lifted to actuate any parts for reversing the flow of liquid.

What I claim as my invention is:—

1. A hydrostatic jack provided with a return passage for reversing the flow of liquid to lower the movable part of the jack; a pump having a hinged connection with the jack; and means for controlling the flow of liquid through the said passage formed in the hinged connection between the pump and the jack.
2. A hydrostatic jack provided with a return passage for reversing the flow of liquid to lower the movable part of the jack; a pump; a rigid conduit having a hinged connection with the jack and the pump barrel; and means for controlling the flow of liquid through the said passage formed in the hinged connection between the conduit and the jack.
3. A hydrostatic jack provided with a return passage for reversing the flow of liquid to lower the movable part of the jack; a pump; a rigid conduit having a hinged connection with the pump barrel; a pipe joint for connecting the conduit with the jack and provided with a plug adapted to control the flow of liquid through the said passage, the plug being provided with means adapted to form a communication between the ends of the said passage when the plug is oscillated to bring the communicating means into register with the ends of the passage.
4. In a hydrostatic jack the combination with a cylinder having a tubular plunger slidably mounted therein, the jack being provided with a passage and provided with a valve controlled passage forming a communication with the first mentioned passage and the cylinder below the plunger and provided with a valve controlled passage forming a communication with the first mentioned passage and the interior of the plunger, a pump, a conduit having a hinged connection with the pump barrel, a pipe joint for connecting the conduit with the jack and forming a communication with the first mentioned passage and including a plug and bearing thereon, of a lifting shoe carried by the upper end of the plunger and having a controlled return passage formed therein, one end of which forms a communication between the first mentioned valve controlled passage below the valve and the opening in the bearing for the said plug, the other end of the return passage forming a communication between the second mentioned valve controlled passage below the valve and the opening in the bearing for the plug, the plug being adapted to control the flow of liquid through the return passage and having a groove formed longitudinally therein adapted to form a communication between the ends of the return passage, the

plug being adapted to be oscillated to bring the groove into register with the ends of the return passage when the pump barrel is lowered relative to its position for raising the lifting shoe.

5. In a hydrostatic jack the combination of a cylinder; a tubular plunger slidably mounted in the cylinder and having its upper end closed; a pump adapted to deliver liquid from the interior of the plunger to the underside thereof, the jack having a return passage for reversing the flow of liquid to lower the plunger, the latter having a normally closed aperture adapted to automatically admit air into the upper end of the plunger to replace the liquid pumped therefrom, the plunger having an air outlet opening communicating with the upper end of the interior of the plunger; and means for controlling the exit of the air through the outlet opening and the flow of liquid through the return passage.

6. In a hydrostatic jack the combination of a cylinder; a tubular plunger slidably mounted in the cylinder and having its upper end closed; a pump having a hinged connection with the jack and adapted to deliver liquid from the interior of the plunger to the underside thereof, the jack having a return passage for reversing the flow of liquid to lower the plunger, the latter having a normally closed aperture adapted to automatically admit air into the upper end of the plunger to replace the liquid pumped therefrom, the plunger having an air outlet opening; and means for controlling the exit of the air through the outlet opening and the flow of liquid through the return passage adapted to be actuated by raising and lowering the free end of the pump barrel.

7. In a hydrostatic jack the combination of a cylinder; a tubular plunger slidably mounted in the cylinder and having its upper end closed; a pump having a hinged connection with the jack adapted to deliver liquid from the interior of the plunger to the underside thereof, the jack having a return passage for reversing the flow of liquid to lower the plunger, the latter having a normally closed aperture adapted to automatically admit air into the upper end of the plunger to replace the liquid pumped therefrom, the plunger having an air outlet opening; and means formed in the hinged connection between the pump and the jack for controlling the exit of the air through the outlet opening and the flow of liquid through the return passage.

8. In a hydrostatic jack the combination of a cylinder; a tubular plunger slidably mounted therein and having its upper end closed, the jack having passages controlled by check valves for leading liquid from the interior of the plunger to the underside

thereof; a pump having a pipe joint connection with the jack for delivering the liquid through the said passages, the said connection including a plug and bearing therefor, the jack having return passages for reversing the flow of liquid to lower the plunger, each return passage communicating with one of the first mentioned passages and with the opening in the plug bearing, the plug having an opening com-

municating with the pump barrel and adapted to communicate with the first mentioned passages, the plug also being provided with a groove adapted to be brought into register with and form a communication between the ends of the return passages.

Signed at Toronto, Canada, this 8th day of August, 1922.

DALLAS F. GRAHAME.
